UNITED STATES PATENT OFFICE.

OSCAR M. STIEGLER, OF BOSTON, MASSACHUSETTS.

CLAMP FOR USE IN CONNECTION WITH SOCKET CARBON-BRUSH HOLDERS.

SPECIFICATION forming part of Letters Patent No. 733,436, dated July 14, 1903.

Application filed November 8, 1902. Serial No. 130,509. (No model.)

To all whom it may concern:

Be it known that I, OSCAR M. STIEGLER, a citizen of the United States, residing in Boston, in the county of Suffolk and State of Massachusetts, have invented a certain new and useful improvement in clamps to be used in connection with socket carbon-brush holders for the purpose of forming a contact between the carbon brush and the holder by means of thin copper strips attached to the clamp, of which the following is a specification.

The objects of my invention are, first, to have a clamp which can be removed from the carbon brush by means of a thumb-nut without taking either nut or screw from the clamp; second, to have a clamp which will adjust itself to the variations in thickness of carbon brushes, and thus form a good contact. I obtain these objects by the mechanism illustrated in the accompanying drawings, in which—

Figure 1 represents the sheet-metal punching of the clamp. Fig. 2 is a side view of the clamp when formed into shape, showing screw and thumb-nut. Fig. 3 is a front view. Fig. 4 is a top view. Figs. 5 and 6 are views of a socket carbon-brush holder, showing the clamp attached to carbon brush. Fig. 7 represents a carbon brush slotted at one end.

Referring to Fig. 1, *a a* form the top and bottom of the clamp between which the carbon, Fig. 7, is clamped, as shown in Figs. 5 and 6. *b b* are the ends which form the ears or loops into which the copper strips *i* are fastened and may be screwed to any part of the holder, as shown in Fig. 5.

Fig. 2 is a side view of the clamp, of which *d* is a thumb-nut; *c*, a bolt with a square un-

der the head fitting into the square hole, and thus preventing it from turning when loosened or tightened by thumb-nut *d*. Small circles are formed at points *e* for the purpose of making the clamp more pliable, and thus forming itself to the variations of thickness 45 of carbon brushes. *b b* are the ears or loops, as also shown in Figs. 3 and 4, being bent in opposite direction from *a a*, into which the thin copper strips are fastened.

Fig. 3 is a front view of the clamp, and Fig. 50 4 is a top view.

Figs. 5 and 6 are views of a socket carbon-brush holder, showing the carbon brush in the socket with the clamp attached. *i* represents thin copper strips carrying the current 55 to the brush-holder. Fig. 7 represents views of a carbon brush, of which *f* is a slot which admits bolt *c*, thus allowing the clamp to be attached without removing the bolt.

I do not know of any clamp of a similar 60 construction ever having been used in connection with a slotted carbon brush for the purpose specified.

I therefore desire to secure by Letters Patent—

1. A clamp formed of sheet metal, the corners being formed into half-circles, with ears or loops in the opposite direction of the clamping parts, for the purpose specified.

2. The combination of a clamp formed of 70 sheet metal with ears or loops bent in the opposite direction from the clamping parts and a carbon brush with a slot at one end for the purpose specified.

OSCAR M. STIEGLER.
